Primary Examiner — Paula Allen Greene(74) *Attorney, Agent, or Firm* — Robert L. Stearns;
 Dickinson Wright, PLLC(57) **CLAIM**

The ornamental design for a pair of earbuds, as shown and described.

DESCRIPTION

FIG. 1 is a bottom perspective view of a pair of earbuds;
 FIG. 2 is a top perspective view of a pair of earbuds;
 FIG. 3 is a front view of the pair of earbuds;
 FIG. 4 is a rear view of the pair of earbuds;
 FIG. 5 is a left side view of the pair of earbuds;
 FIG. 6 is a right side view of the pair of earbuds;
 FIG. 7 is a bottom view of the pair of earbuds; and,
 FIG. 8 is top view of the pair of earbuds.

The broken lines depict portions of the pair of earbuds that form no part of the claimed design.

1 Claim, 8 Drawing Sheets(56)
